(57) **CLAIM**

The ornamental design for a shoe heel, as shown and described.

DESCRIPTION

FIG. 1 shows a perspective view of the present design, wherein the broken lines are shown for illustrative purposes only and forms no part of the claimed design.

FIG. 2 shows a front view of the present design, wherein the broken lines are shown for illustrative purposes only and forms no part of the claimed design; and,

FIG. 3 shows a left view of the present design, wherein the broken lines are shown for illustrative purposes only and forms no part of the claimed design.

The interior of the shoe heel is smooth and follows the contour of the heel.
